UNITED STATES PATENT OFFICE.

WILLIAM H. JACKSON AND JOHN H. HANKINSON, OF NEW YORK, N. Y.

DESIGN FOR A FIRE-PLACE BACK.

SPECIFICATION forming part of Design No. 14,378, dated October 30, 1883.

Application filed July 25, 1883. Term of patent 7 years.

To all whom it may concern:

Be it known that we, WILLIAM H. JACKSON and JOHN H. HANKINSON, citizens of the United States, residing at New York, in the county of New York and State of New York, have invented and produced a new and original Design for Fire-Place Backs, designated as the "Griffin Cast," of which the following is a specification, reference being had to the accompanying drawing, forming part thereof.

The drawing represents this new design for fire-place backs as viewed in elevation.

This design, viewed in elevation, presents in appearance a shrub or small tree above a balustrade. The limbs and foliage are like the myrtle, and spreading at each side of an architectural vertical stand or trunk, and overspreading ideal figures with heads, wings, and crouching curved bodies somewhat resembling the griffin as exhibited in Greek architecture. The two crouched griffin figures face outwardly, with their hinder feet apparently connected with the stand or pedestal, and their front feet resting upon the top rail or coping of the balustrade that extends across the bottom of the design and constitutes its base.

The pedestal of the stand, which represents

the trunk of the shrub or tree, is seated in the center of the top rail or coping of the balustrade, and presents the appearance of a collared cone with its apex downward. The top of this architectural trunk or stand terminates with a standing leaf, like that of the oak. Between the pedestal and the crowning leaf the trunk or stand consists of sections representing circular capped pillars and an oval-shaped vertically-fluted vase.

The balustrade consists of open-work resembling symmetrical flattened links with short intervening connecting-loops, and supporting at their upper ends, on short necks, two plane longitudinal caps or rails as coping.

Having described our invention, we claim—

The design for a fire-place back herein shown and described, representing in relief a shrub or tree, with an artificial trunk, and limbs and foliage overspreading figures of ideal griffins above a balustrade forming the lower part of the design.

WILLIAM H. JACKSON.
JOHN H. HANKINSON.
